SPRAYING DEVICE

Mary E. Altergott, Chicago, Ill.

Application November 10, 1953, Serial No. 391,271

2 Claims. (Cl. 299—90)

2

Figure 2 is an enlarged central vertical sectional view of the structure of Fig. 1, indicating the operation of the device, in exaggerated style, for spraying at a downward angle;

5 Figure 3 is an enlarged top plan view of the closure or cap element only;

Figure 4 is a fragmentary central vertical sectional view illustrating a modified form of closure or cap element; and

10 Figure 5 is a top plan view of the closure element of Fig. 4.

As shown on the drawings:

The illustrated embodiment of the instant invention shown in Figs. 1 to 3 inclusive, comprises a container 1 which, for illustrative purposes, is shown in the form of a bottle having a relatively narrow neck 2 provided with an outstanding integral thread 3 to accommodate a screw type cap. Now with reference to Fig. 4, which shows the same bottle or container construction, it will be noted that the threads do not start at the outer edge of the neck, but are spaced inwardly therefrom a distance sufficient to provide a true cylindrical and smooth side portion 4, and the outer edge of the neck is cut off or terminates squarely to provide a flat annular shoulder 5 surrounding the mouth of the container.

This bottle or container 1 is preferably made entirely in one piece and of a suitable lightweight plastic material such as polyethylene. The bottom and upper shoulder of the container may be thickened or otherwise made stiff, 30 but the side wall of the container is readily flexible as shown in Fig. 2, wherein the wall is illustrated as squeezed inwardly at 6, from the normal position of the wall indicated by the dotted lines. Of course, the resilient wall, when released, automatically assumes normal position as seen in Fig. 1, or as denoted by the dotted lines of Fig. 2.

Again with reference to Figs. 1, 2 and 3, it will be seen that the closure or cap element, generally indicated by numeral 7, comprises a skirt 8 having an integrally threaded portion 9 formed therein, which is complementary to the threads 3 on the bottle, the skirt terminating in a reinforcing bead 10. The upper portion of the skirt is free from knurling or other gripping configuration, to define a smooth cylindrical portion 11 for intimate contact with the smooth cylindrical portion 4 on the bottle neck. The top of the skirted or cup-like cap 17 is also provided with a flat annular portion or rim 12 for intimate contact with the flat outer edge 5 of the bottle neck, as seen in Fig. 2. Inside that flat annular portion 12 the cap is outwardly domed as shown at 13. The major portion of this domed part is imperforate or solid.

Of course, apertures for the discharge of liquid from the bottle are provided in the cap. With reference more particularly to Fig. 3, it will be seen that these apertures 14 are relatively minute in character, are widely spaced, and are disposed in circular formation in the dome portion 13 of the cap, but are preferably immediately adjacent the circumference of that dome portion. In other words, the apertures are preferably in the dome part itself, but located where that dome part rises from the annular flat rim 12. While the apertures may vary in number, depending upon the use to which the spraying device is to be put, six such apertures are highly satisfactory for most ordinary uses. Outside of the single circle of apertures 14, the cap is imperforate.

The complete cap itself may economically be made of metal for durability, or of plastic, if so desired.

In use, it is a simple expedient to remove the cap 7, fill the bottle fully or partially with whatever liquid is desired to be sprayed, and simply screw the cap in place on the bottle neck. The screwing of the cap in place on

This invention relates to improvements in a spraying device, and more particularly to a spraying device highly desirable for dampening clothes prior to ironing the same, although the device will have other uses and purposes, such as watering plants, the spraying of insecticides, etc., as will be apparent to one skilled in the art.

In the past, many and various types of spraying devices have been developed. In many cases these formerly known devices, particularly for dampening clothes, were of the shaker type utilizing a rigid container, an apertured cap, and the device had to be forcibly shaken to discharge the liquid through the cap. The use of such devices resulted in uneven wetting, they were tiresome to the user, and could not satisfactorily be used by the debilitated, elderly, or physically handicapped. Other types of spraying devices heretofore developed involved the use of a container having a resilient wall which, when pressed, caused the forcible discharge of the liquid contents. These devices frequently had a center discharge opening and as such were not arranged to provide anything but a concentrated stream of liquid, rather than a delicate and highly diffused spray. Further, as made heretofore, refillable spraying devices frequently required the addition of a gasket or other sealing means to prevent leakage, which sealing means could become lost or displaced to the aggravation of the user.

With the foregoing in mind, it is in an important object of the instant invention to provide a spraying device that is extremely easy to use, light in weight, and so may properly be handled by the elderly, crippled, or otherwise physically handicapped.

Also an object of this invention is the provision of a spraying device requiring extremely little energy to manipulate, and which is so designed as to provide a delicate highly diffused spray which results in evenly wetting the sprayed surfaces.

Also an object of this invention is the provision of a spraying device including a container with a removable cap, and with which no extraneous sealing means whatever are necessary in order to prevent leakage.

It is also a feature of this invention to provide a simply constructed and economical spraying device, manually manipulated, and which will spray effectively in substantially any direction.

A further feature of the invention resides in the provision of a spraying device comprising a bottle or container made of a plastic material, and having a resilient side wall, with a removable cap that automatically effects sealing engagement with the mouth of the bottle or container when placed in position thereon.

While some of the more salient features, characteristics and advantages of the instant invention have been above pointed out, others will become apparent from the following disclosures, taken in conjunction with the accompanying drawing, in which—

Figure 1 is a side elevational view of a spraying device embodying principles of the instant invention;

the bottle neck effects a liquid tight seal between the smooth cylindrical portion 11 of the cap skirt and the corresponding cylindrical part 4 on the neck of a bottle, and between the annular flat rim 12 of the cap and the outer edge 5 of the bottle neck. No extraneous means such as a gasket are necessary at any time. After the bottle has been so readied, it is a simple expedient to lightly press the sides of the bottle and a delicate highly diffused spray of liquid will emanate in any desired direction. The showing in Fig. 2 is highly exaggerated as to the amount of pressure necessary, and it would not be essential to squeeze the bottle wall to the extent shown in Fig. 2, unless the bottle were practically empty. In fact, a very light compression of the side of the bottle is sufficient to provide a satisfactory spray which accomplishes even wetting of a sprayed surface.

In Figs. 4 and 5 I have illustrated a different form of cap or closure element, generally indicated by numeral 15. This form of cap may well be molded from a plastic or ceramic material and includes an outer hollow dome portion 16 and an elongated externally tapered hollow neck 17. This neck is for insertion inside the bottle neck 2 as seen in Fig. 4, and in this instance extraneous sealing means are necessary, and may satisfactorily be in the form of a sleeve 18 of cork or other suitable material surrounding the neck 17.

As seen more clearly in Fig. 5, the major portion of the dome 16 is imperforate, and spaced well away from the center of the dome is a similar set of minute apertures 19, widely spaced in circular formation.

The use of the embodiment seen in Figs. 4 and 5 is substantially the same as that above described in connection with Figs. 1 to 3 inclusive, although the structure of Figs. 1 to 3 is perhaps more economical and simpler to manipulate.

From the foregoing, it is apparent that I have provided a simple, lightweight, economical and easily operable

spraying device which effects a delicate highly diffused spray for even wetting, and which device may readily be handled by an enfeebled operator.

It will be understood that modifications and variations 5 may be effected without departing from the scope of the novel concepts of the present invention.

I claim as my invention:

10 1. A sprayer comprising a plastic bottle having a flexible side wall and a rigid bottom and narrow neck with a straight cut end and a cylindrical side margin thereadjacent, and a detachable cap for said neck having a skirt smoothly cylindrical at the top and a flat annular portion to overlie the upper edge of the bottle neck, said cap being outwardly domed inside said annular portion, and said cap having a circle of widely spaced minute apertures positioned in the domed portion of said cap immediately adjacent said flat annular radial portion.

20 2. A sprayer comprising a polyethylene bottle having a relatively stiff narrow neck and bottom and a highly flexible side wall, and a detachable cap for said neck having a flat outer annular portion in its top and an outwardly domed solid portion inside of said annular portion, and a plurality of annularly arranged and widely spaced minute apertures in said solid portion immediately adjacent the annular line of intersection between said outwardly domed solid portion and said flat outer annular portion.
